MACHINE GUN FEED

Daniel S. Elliott, Middle River, Md., assignor to
The Glenn L. Martin Company, Baltimore,
Md.

Application June 13, 1941, Serial No. 397,879

3 Claims. (Cl. 89—33)

1

This invention is directed to a power boost for feeding a belt of ammunition to a machine gun.

The ammunition for machine guns is conventionally mounted in a belt which is pulled along by the machine gun itself to feed ammunition to the machine gun. Difficulties are encountered, however, when the drum or roll of ammunition is located at some distance from the machine gun, as the weight of the belt between the drum and the machine gun becomes quite heavy and the actuating mechanism of the machine gun is not powerful enough to draw the belt along as fast as it should move. As the belt slows in its travel the machine gun can not fire as rapidly as before and therefore its firing power diminishes, and in some instances the slowing of the belt may cause the machine gun to jam. In aircraft construction, in particular, it is desirable to locate the drum or drums of ammunition at some distance from the machine gun and thus a relatively long path exists for a belt of ammunition to travel from the drum to the gun.

The object of the instant invention is to provide a power boost for aiding the movement of the belt of ammunition as it passes from the drum to the gun, thereby making a relatively long belt of ammunition possible without causing difficulties at the gun.

Another object of the invention is to construct a power boost mechanism which is automatically brought into operation when the belt tends to slow down in its movement from the drum to the gun.

Another object of the invention is to produce a booster unit for ammunition feed, which has a mean rate of feed equal to the rate of feed provided by the automatic gun, and need not be synchronized with the gun.

Another object of the invention is to take a considerable part of the drag load of the belt from the gun so that the gun can fire at its maximum firing rate.

Another object of the invention is to produce a motor driven booster for facilitating the movement of an ammunition belt, in which the rate of ammunition feed is controlled in part by the belt to start and stop intermittently the motor.

Another object of the invention is to produce an all electric powered feed boost for machine guns.

Generally these objects of the invention are obtained by providing motor driven sprocket wheels engaging the belt of ammunition between the ammunition drum and the machine gun.

2

The motor for actuating the sprocket wheels is automatically started or stopped in dependence upon the amount of pull exerted by the belt which in turn is pulled by the machine gun. When the motor is operated, the belt is driven by the sprockets at a speed greater than the maximum firing rate of the gun. If desired a series of motors and sprockets may be placed in tandem and actuated by common control so that a belt of 10 long length may be fed from the ammunition drum to the gun without producing more than the desired load upon the gun.

A means by which the objects of this invention are obtained is more clearly shown in the accompanying drawings in which:

Fig. 1 is a side elevational view of a motor driven sprocket for propelling an ammunition belt;

Fig. 2 is a plan view of Fig. 1;

Fig. 3 is an end elevational view of Fig. 1;
Fig. 4 is a diagrammatical view illustrating the electric circuit for operating two booster units in tandem; and

Fig. 5 is a side elevational view illustrating 25 two booster units mounted in tandem.

Figure 6 is an enlarged fragmentary sectional view of the mounting of the sprockets on the drive shaft.

Figure 7 is a section taken on the line 7—7 of 30 Figure 6.

In Fig. 1, a machine gun diagrammatically illustrated at A, is fed with a belt of ammunition B. Normally the machine gun itself draws the belt of ammunition into the machine gun. However, when the ammunition drum C is located at some distance from the machine gun, the drag of the ammunition belt becomes too great for the machine gun to pull the belt along at a rate sufficient to feed bullets to the gun as fast as the gun is capable of firing.

To aid in the feeding of an ammunition belt the novel booster unit of the instant invention is employed. The ammunition belt B passes through a box-shaped trough 2 where either the belt itself or the bullets in the belt are engaged by a pair of spaced sprocket wheels 4 and 6. A leaf spring 8 on the bottom of trough 2 lifts the belt from the trough to reduce friction therewith and urges the ammunition belt into engagement with the teeth of the sprocket wheels, which teeth project downwardly through slots in the cover plate 3 into the trough. A spring 10, Fig. 2, mounted on the side of trough 2, holds the belt in longitudinal position as it passes through the trough, it being noted that this spring is not

necessary if the trough is of proper width for the belt.

In the embodiment of the invention shown, the sprocket wheels are driven by an electric motor 12, the shaft of which is geared to the shaft 14 upon which the sprocket wheels are mounted. Motor 12 is mounted on top as shown, or on bottom of the trough 2 opposite spring 8, and is adapted to drive the sprockets at a speed greater than the maximum firing rate of the gun.

As the belt of ammunition leaves trough 2 it passes through a tubular shelf 16 which is hinged at 18 to the discharge end of the trough 2 so that the tubular shelf 16 can rotate upwardly. Mounted on the bottom of trough 2 near hinge 18 is an electric switch 20 having a conventional push button 22 holding the switch in normal open position when the shelf 16 is down as illustrated in full lines in Fig. 1. An arm 24 depends from the side of tubular shelf 16, this arm carrying an adjustable screw 26. The free end of this screw engages a leaf spring 28 supported at one end on trough 2, which in turn presses upon the push button 22 to keep the switch contacts normally open. In some instances, it is desirable to have motor 12 and the sprockets mounted on shelf 16 and swingable therewith.

The operation of this booster unit is as follows: As is illustrated in Fig. 1, the machine gun is mounted above and substantially perpendicular to the shelf 16. In general, the gun is positioned with respect to shelf 16 so that a pull on the belt will lift the shelf. Normally the ammunition belt B extends through aligned trough 2 and shelf 16 when shelf 16 is in its down position. When the gunner depresses the trigger on the gun and the gun begins firing, the ammunition belt and shelf 16 begin to rise toward the position shown in dotted lines, Fig. 2, this being because of the drag on the belt. As shelf 16 moves, the arm 24 moves screw 26 away from the spring 28, push button 22 thus moving outwardly to close the switch and to start motor 12. Sprockets 4 and 6 are thereupon put in motion by motor 12 and drive the ammunition belt forwardly. Shelf 16 continues to rise under the pull of the belt as the sprocket wheels 4 and 6 pick up speed, this rising continuing until the speed of wheels 4 and 6 equals the rate of feed to the gun. Thereafter the motor feeds the ammunition belt faster than the shells are consumed by the gun, and accordingly slack is created in the ammunition belt between the sprocket wheels and machine gun A, this causing the shelf 16 to drop, and the cycle begins again. Consequently the rate of feed of the bullets to the gun is controlled by the booster unit, which in turn is controlled by the pull of the ammunition belt on the shelf, the motor being started or stopped by the shelf movement. The maximum speed of the sprockets driven by their motor is always greater than the maximum firing rate of the gun. By this means it is insured that bullets are available for the machine gun at all times. Furthermore, the booster unit moves the belt at a mean speed substantially equal to that of the machine gun feed, and without necessarily being synchronized with the machine gun feed. In order to avoid a braking action on the part of the motor if the motor should jam, or the motor circuits should fail, overrunning clutches of conventional design can be included between the sprocket wheels and their supporting shaft. This eliminates the possibility of stoppage of the machine gun even though the booster unit became in-

operative. Such a clutch is illustrated in Figures 6 and 7. Figure 6 shows an enlarged sectional view of the hub of sprocket 6 mounted on shaft 14. Sprocket 6 is free to rotate on shaft 14 and as will be seen from Figure 7, and includes a one way friction clutch to cause sprocket 6 to be driven by shaft 14. This clutch mechanism consists of a plate 40 secured to rotate with shaft 14 having a flange portion 41 extending around portion 42 of the hub of sprocket 6. The periphery of portion 42 is formed with eccentric surfaces 43 that form with the inner wall of member 41, a tapered channel. Pockets 44 are formed at the larger ends of the tapered channels. Balls 45 are placed in the channels and are of such a diameter that when in the pocket or the enlarged end of the channel, they have considerable clearance but their diameter must be more than the narrow end of the tapered channel. It can be seen from a consideration of Figures 6 and 7 that sprocket 6, which is secured to and turns with member 42, can rotate freely in a counterclockwise direction when the shaft 14 and flange 41 remain stationary, but when the motor drives shaft 14 and flange 41, the balls will be wedged between member 42 and 41 in the tapered channel and for counterclockwise rotation, sprocket 6 will be driven by shaft 14. When shaft 14 stops, sprocket 6 may continue to move because the balls 45 will move toward the enlarged end of the channel or the pockets 44 out of frictional engagement with members 41 and 42. This type of mechanism is often referred to as a one-way clutch because sprocket 6 may freely move in a clockwise (see part 42 in Figure 7) direction relative to shaft 14 but is prevented from moving in a counterclockwise (see part 42 in Figure 7) direction when shaft 14 remains stationary.

When the ammunition belt must travel an unusually long distance from the ammunition drum to the machine gun, two motor driven sprocket units 30 and 32 may be placed upon a trough 34 as illustrated in Fig. 5. A swingable shelf 36 actuates a switch 38 exactly as described for Figs. 1 to 3. As shown in Fig. 4, switch 38 is connected in parallel to motor units 30 and 32 so that both motors are simultaneously controlled by switch 38.

The invention therefore provides a means for positively driving the ammunition belt from the ammunition drum to the machine gun so that ammunition is always available for the machine gun, and no undue pull such as would result in slowing down or stoppage of the machine gun can occur because of the length of the travel between the ammunition drum and the machine gun. The operation of the booster unit is automatic and dependent upon the rate of feed demanded by the machine gun. It is to be understood that the power boost disclosed can be used for automatic guns of all calibers, including automatic cannons.

Having now described the means by which the objects of the invention are obtained, I claim:

1. A power booster for the ammunition belt of a machine gun comprising a hollow trough through which said belt of ammunition is adapted to move an electric motor and a control circuit therefor, a sprocket wheel driven by said motor mounted upon said trough with the teeth of said sprocket wheel projecting into said trough to engage said ammunition, a hollow member through which the ammunition is adapted to move, hinged to and normally aligned with said trough, said hollow

member being adapted to be moved out of alignment by the belt when the gun exerts a tension on said belt, and an electric switch to control said motor circuit, said switch being mounted for actuation by movement of said hollow member from the normal position upon tensioning of said belt whereby said motor is energized to furnish additional power to move said belt simultaneously with the action of said gun on said belt.

2. In a machine gun feed device, a power booster for an ammunition belt, said booster comprising a hollow trough through which said belt of ammunition is adapted to move, said trough having an end section thereof, adapted to be positioned adjacent the gun, hinged with respect to the remainder of said trough, an electric motor and a control circuit therefor, a sprocket wheel driven by said motor and mounted upon said trough with the teeth of said sprocket wheel projecting into said trough to engage said belt of ammunition, said hinged portion being adapted to be moved relative to the remainder of said trough by the belt of ammunition when the gun exerts a tension on said belt, and an electric switch in said circuit to control said motor, said switch being mounted on said device for actuation by movement of said hinged section of the trough from the normal position upon tensioning of said belt whereby said motor is energized to furnish additional power to move said belt simultaneously with the action of said gun on said belt.

3. In combination, an automatic gun, a belt of ammunition, means operated by the automatic

action of the gun for pulling the belt toward the gun, a track to guide the belt, and a booster unit for moving the belt in the track; said unit comprising a sprocket wheel arranged to engage said belt, a motor to drive said sprocket wheel, means to actuate the motor in response to the tension in the belt created by the firing of the gun, said motor and sprocket wheel being mounted to maintain the sprocket wheel in the path of the belt, and an overrunning clutch between the motor and the sprocket wheel so constructed and arranged that the belt may be advanced by the automatic action of the gun independent of the motor.
